UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed March 31, 1922. Serial No. 543,289.

To all whom it may concern:

Be it known that I, CHARLES DAVID BONSALL, a citizen of the United States, and a resident of the city of Pittsburgh, county 5 of Allegheny, and State of Pennsylvania, have invented a new and useful Improvement in Car Roofs, of which the following is a specification.

This invention relates principally to all- 10 steel riveted-up car roofs of the kind shown in my pending application Ser. No. 516,600 filed November 21, 1921, wherein the roofing sheets extend from side plate to side plate and are formed along their side margins with 15 channeled portions that are lapped portions and riveted together to form weather proofing hollow box-girder joints or seams that function as carlines.

The principal object of the present invention 20 is to reduce the number of channeled sheets required for roofs of the above type and thereby save the cost of pressing such sheets. Other objects are to reduce the weight of the roof to increase the strength 25 thereof and to facilitate assembly. The invention consists principally in forming a roof of the above type by means of alternately arranged sheets of two types; and it also consists in the parts and arrangements 30 and combinations of parts hereinafter described and claimed.

In the accompanying drawing, wherein like symbols refer to like parts wherever they occur,

35 Fig. 1 is a plan view of an end portion of a car roof embodying my invention;

Fig. 2 is an enlarged transverse section through one half of the roof on the line 2—2 in Fig. 1;

40 Fig. 3 is a longitudinal cross-section through the ridge portion of the roof on the line 3—3 in Fig. 1;

Fig. 4 is a longitudinal cross-section through a portion of the roof between the 45 ridge and the eaves on the line 4—4 in Fig. 1;

Fig. 5 is a similar section through the eaves portion of the car on the line 5—5 in Fig. 1; and

50 Figs. 6 and 7 are longitudinal ridge sections embodying modified forms of roof constructions.

The roof shown in Figs. 1 to 5, inclusive, of the accompanying drawing comprises

heavy gage roof sheets which extend from 55 eaves to eaves of the car. The roof sheets are supported at their eaves ends on the outwardly extending flanges of angle bar side plates 9 and are rigidly secured thereto by rivets 10. The roof sheets are preferably 60 provided with depending drip flanges 11 that overhang the outer edges of said side plates 9. The roof sheets are of two types, the sheets of one type alternating with those of 65 the other type. The roof sheets of the type A are in the form of flat rectangular sheets; and the roof sheets of the type B have strengthening ribs or channels 12 and 13 pressed therein adjacent to their respective 70 side margins, the channels 12 at one side margin of a sheet opening upwardly and the channels 13 at the opposite side margin of said sheet opening downwardly. The ribs 12 and 13 have a minimum width at the 75 ridge and widen gradually to the eaves and are of gradual decreasing depth from ridge to the eaves.

The sheets of the two types are arranged alternately and are assembled by lapping 80 their side marginal portions; that is, the downwardly opening rib 13 in one side margin of a type B sheet overlap one side marginal portion of a flat type A sheet, whose opposite side marginal portion overlaps the 85 upwardly opening rib in one side margin of another type B sheet. The overlapped portions of said sheets are rigidly secured together on opposite sides of the ribs by rows 90 of rivets 14. Thus, the overlapping downwardly opening ribs 13 of the type B sheets 95 cooperate with the underlapping marginal portions of the type A sheets to form exterior hollow box-girder seams or joints, and the underlapping upwardly opening ribs 12 of said type B sheets cooperate with the overlapping marginal portions of said type A sheets to form exterior hollow box-girder 100 seams or joints which alternate with said exterior box-girder seams or joints.

The ribs 12 and 13 of the type B sheets are 105 preferably of channel section and gradually decrease in depth and height, respectively, from the ridge towards the eaves where they merge into the plane of the body of the sheets. The upwardly opening ribs 12 merge into the body of the sheets at the inner faces of the side plates; whereas the downwardly opening ribs merge abruptly into the body

of the sheet at the point where the eaves ends of the sheets are turned down to form depending drip flanges 11.

The sheets of the type B are pressed from 5 sheet blanks having parallel sides, with the result that the gradual decreased depths of the reversely opening channels 12 and 13 creates a surplus of metal that is utilized in securing a uniform widening of sheets, together with the channels 12 and 13 therein, from ridge towards the eaves. This arrangement produces a box-girder seam construction of deep and narrow section at the ridge, that is well adapted to withstand the vertical roof load, and a broad flat section at the eaves that functions as a gusset to withstand horizontal stresses.

Running boards 15 are arranged lengthwise of the car at the ridge and are securely bolted to the uppermost lateral flanges of Z-shaped running board saddles 16, whose lowermost lateral flanges rest on the roof sheets and are secured thereto by rivets that rigidly connect the overlapping side marginal portions of adjacent sheets.

Flat end sheets of the type A are provided for each end of the car. The outer side marginal portions of the end sheets are supported on end plates 17 and are formed with depending drip flanges 19 which overhang the outer edges of said end plates. The inner side marginal portions of the end sheets are rigidly secured to the adjacent channeled marginal portions of the type B sheets and cooperate therewith to form exterior or interior hollow box-girder seams.

It is noted that the alternation of the flat sheets with the channeled sheets, reduces the number of channeled sheets required for 40 roofs of the box-girder seam type, which sheets are expensive to manufacture by reason of the pressing operation required to form the channels therein. It is also noted alternating arrangement of the interior and exterior box-girder joints places the neutral axis of the roof in the plane of the body of the sheets, whereby the maximum strength of the metal is obtained for carrying the roof load.

50 In the modification shown in Fig. 6, roof sheets 20, similar to those of the type B, are provided adjacent to their side marginal portions, with downwardly opening channels 21 that overlap the adjacent side marginal portions of flat sheets of the type A, thereby forming a roof construction wherein all of the box-girder joints are located outside of the roof.

60 In the modification shown in Fig. 7, the roof sheets 20 are arranged with their ribs opening upwardly, and the marginal portions of the flat type A sheets overlap said ribs and are rigidly secured thereto to form interior carlines.

65 Obviously, my invention admits of consid-

erable modification in the designs of the seams or ribs and I do not wish to be limited to the specific designs illustrated.

What I claim is:

1. A car roof comprising a series of roof sheets connected by raised seams alternating with depressed seams. 70

2. A car roof comprising a series of roof sheets connected by box-girder seams, some of said seams being located above the plane 75 of the roof and other of said seams being located below the plane of the roof.

3. A car roof comprising a series of roof sheets connected along their side margins by exterior box-girder seams alternating 80 with interior box-girder seams.

4. A car roof comprising a series of roof sheets connected along their side margins by exterior box-girder seams of varying 85 width from ridge to eaves alternating with interior box-girder seams of varying width from ridge to eaves.

5. A car roof comprising a series of roof sheets connected along their side margins by exterior box-girder seams of varying 90 depth from ridge to eaves alternating with interior box-girder seams of varying depth from ridge to eaves.

6. A car roof comprising a plurality of metal roof sheets connected along their side 95 margins by exterior box-girder seams of varying width and depth from ridge to eaves alternating with interior box-girder seams of varying width and depth from ridge to eaves. 100

7. A car roof comprising flat roof sheets alternating with roof sheets having hollow ribs formed in their side marginal portions, said sheets being arranged with their side 105 marginal portions lapping each other and rigidly secured together to form hollow-box-girder seams.

8. A car roof comprising flat roof sheets alternating with roof sheets having hollow ribs formed in their side marginal portions, 110 said sheets being arranged with their side marginal portions lapping each other and rigidly secured together to form hollow-box-girder seams, the lapped portions of said sheets being rigidly secured together on opposite sides of said hollow ribs to form hollow box-girder seams. 115

9. A car roof comprising flat roof sheets alternating with roof sheets having reverse hollow ribs formed in their side margins, 120 said roof sheets being arranged with their side marginal portions lapping each other and rigidly secured together to form alternating exterior and interior box-girder seams. 125

10. A car roof comprising flat roof sheets alternating with roof sheets having reverse hollow ribs formed in their side margins, 130 said ribs varying in depth from ridge to eaves, said roof sheets being arranged with

their side marginal portions lapping each other to form alternating exterior and interior hollow box-girder seams of varying depth from ridge to eaves.

- 5 11. A car roof comprising flat roof sheets alternating with roof sheets having reverse hollow ribs formed in their side margins, said ribs varying in width from ridge to eaves, said roof sheets being arranged with 10 their side margins lapping and rigidly secured together on each side of a rib to form alternating interior and exterior box-girder seams of varying width from ridge to eaves.
- 15 12. A car roof comprising flat roof sheets alternating with roof sheets having reverse hollow ribs formed in their side marginal portions, said ribs varying in width and depth from the ridge to eaves, said roof

sheets being arranged with their side marginal portions lapping each other to form alternating exterior and interior hollow box-girder seams that vary in width and depth from ridge to eaves.

13. A car roof comprising a plurality of 25 metal roof sheets extending from eaves to eaves with their side margins lapping each other and rigidly secured together along two lines, the portion of the lower sheets between some lines being formed into channels 30 and the portions of the upper sheets between other lines being formed into an inverted channel, said channels being arranged alternatively.

Signed at New Kensington, Pa., this 27th 35 day of March, 1922.

CHARLES DAVID BONSALL.
